(57) **CLAIM**

The ornamental design for a microphone, as shown and described.

DESCRIPTION

FIG. 1 is a front perspective view of a microphone, wherein a stand is in an unfolded position;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left-side elevational view thereof;

FIG. 8 is a right-side elevational view thereof; and,

FIG. 9 is alternative configuration for a front perspective view thereof, wherein a stand is in a folded position.

The broken line showing of buttons in FIGS. 1, 2, 7, 8, and 9 and the broken line showing of attachment screws in FIG. 1-4 are included for the purpose of showing environmental structure and forms no part of the claimed design.
